UNITED STATES PATENT OFFICE.

EDMOND BOUDREAU, OF MORGAN CITY, LOUISIANA.

OIL-BURNER.

1,051,672.

Specification of Letters Patent. Patented Jan. 28, 1913.

Application filed June 17, 1912. Serial No. 704,181.

To all whom it may concern:

Be it known that I, EDMOND BOUDREAU, a citizen of the United States, residing at Morgan City, in the parish of St. Mary and 5 State of Louisiana, have invented a new and useful Oil-Burner, of which the following is a specification.

This invention relates to liquid fuel burners and aims to provide a simple and efficient burner capable of producing a high 10 degree of combustion to provide a maximum heating effect with a minimum fuel supply.

As a further object, the present invention contemplates a liquid fuel burner wherein 15 the fuel is heated by steam or other heated fluid and is then atomized and sprayed by the steam in an effective manner.

The present invention further aims to provide a burner of the character indicated 20 so that the flame may be regulated and may be deflected out of its normal path.

With the foregoing general objects outlined, and other objects in view which will be apparent as the invention is better understood, the present invention resides in the 25 novel construction and combination of parts hereinafter set forth and claimed, it being understood that this device is susceptible of alterations or deviations within its 30 details within the scope of the appended claims without departing from the spirit of the invention.

The present invention has been illustrated in its preferred embodiment in the accompanying drawings, wherein:

Figure 1 is a longitudinal central section of the burner. Fig. 2 is an end view thereof. Fig. 3 is a sectional view taken on the line 3-3 of Fig. 1.

Referring specifically to the drawing, the burner embodies a cruciform body or casing 4 having a partition 5 therein forming an oil chamber 6 and a steam chamber 7. A steam pipe 8 is connected to one arm 45 of the body 4 and communicates with the steam chamber 7 and an oil or liquid fuel pipe 9 is connected to the opposite arm of the body 4, which latter arm communicates with the oil chamber 6. A bonnet 10 is engaged on one of the other arms of the body 4, or that arm communicating with the oil 50 chamber 6 at right angles to the arm to which the pipe 9 is attached. To the partition 5 there is attached a short tube or sleeve 55 11, and which passes through the arm of the body 4 opposite the arm to which the bonnet

10 is attached, the said tube or sleeve opening through the partition 5 into the oil chamber 6.

A tapering steam pipe 12 is engaged to the arm of the body 4 which is opposite the bonnet 10, and a fuel pipe 13 is arranged within the steam pipe 12 and is engaged to the free end of the tube or sleeve 11. The pipes 12 and 13 are concentric and both taper outwardly or forwardly, the steam pipe 12 completely encompassing the fuel pipe 13. A needle valve 14 is screw-threaded through the bonnet 10 and passes axially forward within the fuel pipe 13 so that its 70 tip is arranged adjacent the outer or forward end of the pipe 13. The inner or rear end of the needle valve 14 protrudes beyond the bonnet 10 and bears a suitable hand wheel 15, by means of which the needle valve 75 may be rotated in order to adjust same longitudinally.

The outer or forward end of the steam pipe 12 is closed by a convex head 16, and from the said head 16 projects a central nipple 80 17 and a pair of opposite and diverging nipples 18, the latter nipples and the former nipple being connected by ribs or webs 26.

The forward or outer end of the pipe 13 is partially closed by an inturned flange 19 85 against which the end 16 of the pipe 12 abuts, the said flange 19 providing a valve seat 20 against which the needle valve 14 is adapted to seat. The nipple 17 communicates with the fuel pipe 13, and the nipples 90 18 communicate with the chamber between the two pipes 12 and 13, or the steam chamber 28.

A nozzle 21 is engaged to the nipple 17, 95 said nozzle having its inner end reduced, as designated by the numeral 27, and screw-threaded into the nipple 17. To the nipples 18 are attached the elbows 22, which have reduced portions 23 projecting from the ends of one of their arms and engaging in the 100 said nipples, and the other arms 24 of the said elbows converge toward each other and are directed forwardly toward the tip of the nozzle 21. These arms 24 provide blast nozzles for directing jets of steam toward the tip of the nozzle 21 and at a point slightly inward from the tip of the nozzle 21, the jets being opposed in meeting at the tip of the nozzle 21. Needle valves 25 105 are screw-threaded through the inner arms 110 of the elbows 22 in alinement with the outer arms 24, and are designed to con-

control the passage of steam through the said elbows.

The foregoing parts may be constructed of any suitable material and may be of various sizes and proportions, the said parts being readily assembled and taken apart.

In using the burner, a pipe 9 is connected with a source of oil or other liquid fuel, and the pipe 8 is connected with a source of steam or other heated fluid, which will cause the liquid fuel and steam to be fed to the oil chamber 6 and steam chamber 7, respectively, within the body 4, from which, the fuel and steam will be admitted into the fuel pipe 13 and the steam chamber 28, respectively. The steam is discharged from the chamber 28 through the elbows 22, the converging jets of steam issuing from the nozzles 24 meeting at the tip of the fuel nozzle 21 and tending to create a vacuum so as to suck or draw the fuel forwardly. The steam within the chamber 28 encompasses the fuel pipe 13 and heats the said pipe and the fuel therein to such a degree as to effectively vaporize the fuel, the vapor thus formed being drawn through the nozzle 21 by the steam jets, so that the vapor will be thoroughly mixed with the steam, and so that the fuel will be effectively atomized. The fuel thus atomized and sprayed assumes the fan like shape, due to the opposed jets of steam, which when striking each other spread in fan like forms and carry therewith the vapor. Ordinarily, the needle valves 25 are adjusted so that the streams or jets of steam have an equal velocity or pressure, thus directing the flames in a plane cutting the axis of the burner, and by adjusting one or the other or both, of the needle valves 25, the flames may be deflected upwardly or downwardly according to the varying pressures of the two jets of steam, as will be understood. The flow of vapor is readily regulated by adjusting the needle valve 14 to and from the seat 20, as will be clearly understood.

A fan like flame is of advantage for the reason that the same covers a considerable area, and is not concentrated like a needle flame, which when being directed toward an object tends to fuse the object. This burner when employed in a boiler will therefore not tend to burn the flues, grate bars or other parts, and at the same time will produce a high degree of combustion for providing a maximum heating effect with a minimum fuel supply. This burner is also of advantage for the reason that the flame may be deflected at various angles which may be found both beneficial and necessary, this being accomplished without moving the burner, simply by setting the needle valves 25.

It has been found in practice that the flame produced by the present burner, when

burning oil, is white, thus indicating a thorough consumption of the fuel. It has also been found that the fuel will not drip from the fuel nozzle 21 and that the fuel is thoroughly and effectively atomized and sprayed by the two steam jets, which in being brought in opposition provide for such results.

This burner is not only useful for heating boilers, but may be employed for various purposes as will be understood by those skilled in the art.

Having thus described the invention what is claimed as new is:—

1. In a liquid fuel burner; a fuel nozzle, a needle valve for the fuel nozzle, a pair of opposite elbows, each having one arm diverging from the butt end of the said nozzle, the other arms of the elbows forming blast nozzles converging toward the tip of the said nozzle, and needle valves adjustable in the former arms of the elbows in alinement with the latter arms.

2. A liquid fuel burner embodying a fuel nozzle, a pair of opposed and converging blast nozzles directed forwardly toward the tip of the fuel nozzle, and independent means for controlling the passage of fluid through each of the said nozzles.

3. A liquid fuel burner embodying a fuel pipe, a steam pipe encompassing same, a nozzle communicating with the end of the fuel pipe, a pair of opposed and converging nozzles communicating with the end of the steam pipe and directed forwardly toward the tip of the said nozzle, and independent means for controlling the passage of fluid through each of the said nozzles.

4. A liquid fuel burner embodying a fuel pipe, a steam pipe encompassing same, a nozzle communicating with the end of the fuel pipe, a pair of opposite elbows each having one of its arms attached to and diverging from the end of the steam pipe, and the other arms of the elbows forming converging nozzles directed forwardly toward the tip of the said nozzle, a needle valve passing forwardly through the fuel pipe to control the passage of fuel through the former nozzle, and needle valves adjustable in the former arms of the elbows in alinement with the latter arms thereof.

5. A liquid fuel burner embodying a fuel pipe, a steam pipe encompassing same and having its forward end abutting against the end of the fuel pipe, the forward end of the steam pipe having a central nipple communicating with the fuel pipe and having a pair of opposite diverging nipples, a nozzle engaged to the former nipple, and a pair of opposite elbows each having one of its arms attached to the latter nipples with their other arms converging and directed forwardly toward the tip of the aforesaid nozzle.

6. A liquid fuel burner embodying a fuel pipe, a steam pipe encompassing same and having its forward end abutting against the end of the fuel pipe, the forward end 5 of the steam pipe having a central nipple communicating with the fuel pipe and having a pair of opposite diverging nipples, a nozzle engaged to the former nipple, a pair of elbows each having one of its arms 10 attached to the diverging nipples, with their other arms converging and directed forwardly toward the tip of the aforesaid nozzle, a needle valve passing through the fuel

pipe and coöperating with the forward end thereof to control the passage of vapor therefrom, and needle valves adjustable in the former arms of the elbows in alinement with the latter arms thereof for controlling the passage of steam through the elbows.

In testimony that I claim the foregoing 20 as my own, I have hereto affixed my signature in the presence of two witnesses.

EDMOND BOUDREAUX.
